UNITED STATES PATENT OFFICE.

GEORGE C. GOOD AND FREDERICK C. GOOD, OF PHILADELPHIA, PENNSYLVANIA.

PORTABLE ELEVATOR.

Application filed March 5, 1927. Serial No. 173,109.

The principal object of this invention is to provide a portable elevator which can be quickly erected, for use in building construction.

5 Another object of the invention is to provide an elevator of the above type which can be quickly extended as the building progresses.

10 Still another object of the invention is to form the upright members of the elevator shaft of light weight steel tubing in sections of such a length that they may be readily handled and superposed one upon the other to form a run-way for the elevator cage.

15 By providing an all-metal elevator shaft of the above character, the inefficient and expensive wooden construction is eliminated, and the time consumed in erecting such a wooden structure is considerably reduced.

20 A portable elevator of the type within the scope of our invention may be repeatedly used without damage to the parts thereof. The details of construction and the operation of the device will be fully disclosed herein-
25 after, reference being had to the accompanying drawings, of which:

Fig. 1 is a face view of a portable elevator constructed according to the principles of our invention;

30 Fig. 2 is a side elevation of the elevator;
Fig. 3 is a sectional elevation of a detail of the invention;

Fig. 4 is an enlarged sectional plan view taken on the line 4—4 of Fig. 1;

35 Fig. 5 is a front elevation of the structure shown in Fig. 4, and

Fig. 6 is a sectional plan view taken on the line 6—6 of Fig. 1.

Referring to the drawings, a base plat-
40 form 1 is provided which is adapted to rest on the ground adjacent a building being constructed. The base platform comprises a series of planks 2 extending transversely of the said platform, and secured at their opposite ends to longitudinally extending angle bars 3, 3.

Immediately adjacent each of the longitudinal edges of the platform 1 and at the center thereof, we provide a foot plate 4, adapted to receive the lower end of a section 5 of steel tubing. Each of the sections 5 is provided at one of its ends with a projecting plug 6 which is adapted to fit within the next lower adjacent section 5, as illustrated in Fig. 3, thus providing guideways 10, 10 for the elevator cage 11. The plug 6 of the low-

ermost tube section 5 fits within the foot plate 4, as illustrated in Fig. 1.

Each of the tube sections 5 is provided with laterally extending projections comprising a short section of angle bar 7, the longitudinal edge of one leg 8 of which is welded or otherwise integrally connected to the tube section 5, as illustrated in Figs. 4 and 5, the second leg 9 of said angle bar section 7 being adapted to receive a strip 12 for purposes hereinafter set forth.

The uppermost angle bar 7 on the lowermost tube section 5 is adapted to receive one end of each of a pair of diagonal brace members 13, 13, the opposite end of which is secured to the longitudinally extending angle bars 3 of the base platform 1. The upright guides 10, 10 are thus held in a vertical position. In use with a building up to and including two and one-half stories high no additional bracing is required.

The elevator cage 11 comprises a platform 11^a having longitudinally extending side bars 11^b to which are secured vertical channel beams 14, 14. Secured to the upper end of the vertically extending channel bars 14, 14 is a cross-beam 15. Diagonal braces 16, 16 are provided between the upright members 14 and the cross-beam 15. Diagonal braces 17, 17 are provided between the ends of the platform 11^a and the vertical members 14, 14, thus bracing the platform longitudinally. Guide shoes 20, 20 are provided on each of the vertical members 14, 90 and are adapted to slide on the uprights 10, 10 of the elevator shaft.

Each of the shoes 20 comprises an annular section 21 adapted to encircle the tube sections 5 of the upright members 10, 10, and flanges 22, 22, integrally connected with the said annular portion 21, adapted to be secured to the channel beams 14, 14 by means of bolts 23, 23 in the present instance. The annular portion 21 of each of the shoes 20 is provided with a cut-out portion or slot 24 adapted to permit the shoe 20 to pass the leg 8 of each of the angle bar members 7 as the elevator moves up and down along the uprights 10, 10.

For the purpose of raising and lower the elevator 11, we provide a head member 25 which is adapted to engage and extend between the two upright members 10, 10 and to support an operating sheave 26, over which a cable 27 is adapted to run. The cable 27 is secured to the cross member 15 of the eleva-

tor 11 at 28, and extends vertically, over the sheave 26, then downward adjacent one of the upright members 10 and around the guide sheave 29, and thereafter is operatively connected to any desired form of hoisting engine located adjacent the base platform 1.

The head member 25 comprises a pair of channel beams 30, 30 secured together by means of bolts 31 and provided adjacent 10 their respective ends with sleeve segments 32, 32, each of which is integrally connected to one of the channel beams 30, 30, as shown in Figs. 4 and 5. The sleeve segments 32, 32 engage the upright members 10, thereby 15 preventing the said upright members from spreading relative to each other.

The sheave 26 is rotatably mounted on a shaft 33 secured in one end of a yoke member 34 which extends over one of the channel beams 30 and is secured thereto by means of a bolt 35, as shown in Figs. 4 and 5.

The openings between the outer parallel vertical edges of the sleeve segments 32, 32 permit the head member 25 to be moved vertically along the upright members 10, 10 25 past the angle bar projections 7, 7, and a split ring 36 is provided on each of the upright members 10 under each of the respective ends of the head member 25. The 30 rings 36 are each provided with a slot 37 which is adapted to permit the said ring to be moved vertically on the respective upright member 10, past the angle bar projections 7, after which it is adapted to be rotated horizontally on the said upright member 10 until the slot 37 is moved out of alignment with the leg 8 of the angle bar section 7, thus the said ring is prevented from moving downward on the upright member 10, and the respective ends of the 35 said member 25 bear on the upper surfaces of the pair of rings 36, which supports the head member 25 in place.

The previously mentioned strips 12 are secured to the legs 9 of the respective bar section 7 by means of bolts 38, 38, and are adapted to receive socket members 40, each of which comprises a rectangular frame having studs 41, 41 integrally connected to one 40 of its faces and extending to each side of the vertical strip 12. Strap members 42, 42 extend between each of the pairs of studs 41, 41 at the side of the strip 12 opposite to that engaged by the rectangular frame 40. The 45 studs 41 are provided with nuts 43 by means of which the rectangular frames 40 may be rigidly clamped to the vertical strips 12.

In operation, a wall x is constructed to a height conveniently reached from the ground level y , after which the base platform 1 is positioned adjacent the wall so constructed. The first tube sections 5, 5 are then positioned in the foot plates 4, 4 50 of the base platform and the brace members 13, 13 set in position. The elevator

cage 11 is preferably attached to the lower sections 5 when the said sections are set in place, or the said elevator cage may be placed on the tube sections 5 after they are set in position. The rings 36 and head member 25 55 may then be placed in position on the tube sections 5, 5. Additional tube sections 5, 5 are then placed on these first sections, and the strips 12 bolted in place to prevent the several superposed sections from coming 60 apart. The head 25 may then be moved vertically along the upright members 10, 10, composed of the superposed tube sections 5, to a desired point thereon, after which the rings 36 are turned as above described and 65 the head member 25 thereby held in position. The cable 27 may be then connected between the elevator cage 11 and the hoisting engine. The rectangular frame members 40 are then moved along the strips 12 70 to a position approximately on a level with the top of the wall x , after which beams 50, 50 may be slipped into the said rectangular frame members 40 and their opposite ends 75 permitted to rest upon the top of the wall x , as shown in Fig. 2. A suitable platform 51 may then be constructed on the beams 50 in such a position as to permit the platform 11^a of the elevator cage 11 to be raised to a 80 position in alignment with the platform 51. 85 The elevator is now in condition for operation. The building material may be loaded onto the platform 11^a of the elevator cage and raised to the level of the platform 51 in the usual manner and for the usual purposes. 90

The head member 25 ties the upper ends of the upright members 10, 10 together and prevents the spreading of these said members. The shoes 20, 20 of the elevator, due 95 to the fact that they engage the tube sections 5 over the greater part of their circumference, prevent the spreading of the upright members 10 at points intermediate the base platform 1 and the head member 100 25, as the elevator 11 is moved up and down the elevator shaft. As the building of the wall x progresses, additional tube sections 5 may be added to the upper ends of the upright members 10, 10 and the strips 12 105 likewise extended to tie these members together, additional frame members 40 being placed on the additional strip sections 12 and beams 50 being placed in these additional frame members and resting upon the wall section as above described. The head member 25, upon slackening of the cable 27, 110 may be raised to the next desired height and locked therein by the rings 36. This operation is repeated without further bracing of the upright members 10 up to a point adapted for use in construction of a two and one-half story building. 115

If a building of greater height is to be constructed, the upright members 10 may 120

be braced to the building under construction by any form of brace members attached to the upright strips 12 in the form of stringers having one end secured to the building and the opposite end nailed or otherwise secured to said strip.

A portable elevator constructed in a manner as above described is particularly adaptable when the building is being constructed of the now popular cinder block. Under the old method of carrying the cinder block by hod, a hod carrier could carry but one block at a time, thus making the cost of comparatively small buildings prohibitive. To replace the hod carrier with the old type of wooden elevator shaft would not better the condition due to the expense connected with the erection of such a device, the material employed in such construction being practically destroyed and unfit for further use after the building was completed.

With our improved type of portable elevator, this cost of material is eliminated due to the fact that the component parts of our construction may be successively used without injury. The time required for erecting the elevator considerably reduces the construction cost, thus the contractor may employ this type of device with a considerable saving of time and money, and thus make the construction of a relatively small building, using the cement block, profitable.

We claim:

1. A portable elevator comprising the combination of a base platform; upright guide members on said platform; lateral projections on said uprights; a head member slidably mounted on said uprights; means cooperating with said head member and the lateral projections on said upright members adapted to maintain said head member in its adjusted position on said upright members; and an elevator car adapted to slide on said upright guide members.

2. A portable elevator comprising the combination of a base platform; upright guide members on said platform; each upright comprising a plurality of superposed tube sections; a foot plate for each upright on said platform; a plug extending longitudinally beyond one end of each tube section and adapted to fit within the opposite end of an adjacent axially aligned tube section or within one of said foot plates; lateral projections on said uprights; a head member slidably mounted on said uprights; means cooperating with said head member and the lateral projections on said upright members adapted to maintain said head member in its adjusted position on said upright members; and an elevator car adapted to slide on said upright guide members.

3. A portable elevator comprising the combination of a base platform; upright guide members on said platform, each up-

right comprising a plurality of superposed tube sections; a foot plate for each upright on said platform; a plug extending longitudinally beyond one end of each tube section and adapted to fit within the opposite end of an adjacent axially aligned tube section or within one of said foot plates; means for bracing the said uprights longitudinally of said base platform; lateral projections on said uprights; a head member slidably mounted on said uprights; means cooperating with said head member and the lateral projections on said upright members adapted to maintain said head member in its adjusted position on said upright members; and an elevator car adapted to slide on said upright guide members.

4. A portable elevator comprising the combination of a base platform; removable upright guide members on said platform; bracing means between said uprights and said base platform; lateral projections on said uprights; a head member slidably mounted on said uprights and provided with slotted ends adapted to permit said head to be moved past said projections; slidable slotted collars on said uprights cooperating with said head member and the lateral projections on said upright members adapted to maintain said head member in its adjusted position on said upright members; and an elevator car adapted to slide on said upright guide members.

5. A portable elevator comprising the combination of a base platform; removable upright guide members on said platform; diagonal bracing members between said platform and said uprights for bracing said uprights longitudinally of said platform; lateral projections on said uprights; a head member slidably mounted on said uprights, and adapted to brace said uprights transversely of said platform; means cooperating with said head member and the lateral projections on said upright members adapted to maintain said head member in its adjusted position on said upright members; an elevator car adapted to slide on said upright guide members; shoes on said car and engaging said uprights in a manner to prevent lateral spreading thereof as the car is moved up and down said uprights.

6. A portable elevator comprising the combination of a base platform; removable upright guide members on said platform; diagonal bracing members between said platform and said uprights for bracing said uprights longitudinally of said platform; lateral projections on said uprights; a head member slidably mounted on said uprights, and adapted to brace said uprights transversely of said platform; means cooperating with said head member and the lateral projections on said upright members adapted to maintain said head member in its ad-

justed position on said upright members; an elevator car adapted to slide on said upright guide members; shoes on said car and engaging said uprights in a manner to prevent lateral spreading thereof as the car is moved up and down said uprights; and slots in said shoes permitting the passage thereof past said lateral projections.

7. A portable elevator comprising the combination of a base platform; upright guide members on said platform, each comprising a plurality of superposed axially aligned tubular sections; lateral projections on said sections; nailing strips secured to and extending between said lateral projections; a head member slidably mounted on said uprights; means cooperating with said head member and the lateral projections on said upright members adapted to maintain said head member in its adjusted position on said upright members; an elevator car adapted to slide on said upright guide members; and floor platform supporting means slidably mounted on said nailing strips and adapted to support a floor platform at a point above said base platform.

8. A portable elevator comprising the combination of a base platform; upright guide members on said platform; lateral projections on said uprights; a head member slidably mounted on said uprights; a sheave wheel rotatably mounted on said head member; means cooperating with said head member and the lateral projections on said upright members adapted to maintain said head member in its adjusted position on said upright members; an elevator car adapted to slide on said upright guide members; and a lifting cable attached to said elevator car and passing over said sheave wheel.

9. In a portable elevator the combination

of upright guide members; lateral projections on said uprights; a head member slidably mounted on said uprights; and means cooperating with said head member and the lateral projections on said upright members adapted to maintain said head member in its adjusted position on said upright members.

10. In a portable elevator, upright guide members, each comprising a plurality of tubular sections adapted to be superposed one upon another; means within the said tube sections adapted to maintain the adjacent sections in axial alignment; lateral projections on each of said sections; a head member slidably mounted on said uprights; and means cooperating with said head member and the lateral projections adapted to maintain said head member in its adjusted position on said upright members.

11. In a portable elevator the combination of upright guide members; lateral projections on said uprights; a head member slidably mounted on said uprights and comprising a pair of similar parallel members each provided with a sleeve segment at each of its opposite ends, adapted to engage said uprights; a vertical slot formed in the outer ends of said head member between said sleeve segments permitting the said head member to pass said lateral projections; means for securing the said two similar parallel members together as a unit; and means cooperating with the sleeve segments of said head member and the lateral projections on said upright members adapted to maintain said head member in its adjusted position on said upright members.
